UNITED STATES PATENT OFFICE.

EDWARD W. SALMON, JR., OF BALTIMORE, MARYLAND, ASSIGNOR TO LEO FESEN-MEIER, OF BALTIMORE, MARYLAND.

FILING AND STORAGE CABINET.

Application filed August 3, 1922. Serial No. 579,452.

To all whom it may concern:

Be it known that I, EDWARD W. SALMON, Jr., a citizen of the United States, residing in the city of Baltimore and State of Maryland, have invented new and useful Improvements in Filing and Storage Cabinets, of which the following is a specification.

This invention relates to cabinets.

One object of the invention is to provide 10 a cabinet particularly adapted for the filing and storage of motion picture films or other combustible or valuable records, embodying among other characteristics, a cabinet provided with a compartment in which a record holding device is mounted for the reception and support of the record material to be preserved and which has connection with a swinging door whereby upon opening of the door, the holder may be swung 20 forwardly to permit ready access thereto and whereby upon release of the door, the holder will move rapidly to its normal position and cause the door to close in sealed relation with the door jamb and thereby exclude moisture and prevent possibility of 25 fire in the cabinet through careless handling of matches, smoking materials or external combustion.

Another object is to provide a record 30 holder embodying a base and a holder supported above the base on suitable connections arranged between the base and holder and wherein the connections are locked to the base by suitable locking devices to prevent 35 accidental disconnection of the mounting between the base and holder.

Another object of the invention is to provide 40 a cabinet having a hinged door to which a movable record holder in the compartment is connected so as to limit outward swinging movement of the door and to effect automatic closing of the door when the operator releases the same.

Another object of the invention resides 45 in the provision of a cabinet of the nature stated, which is constructed of fireproof material and in which the door of the cabinet may be maintained normally locked, there being means remote from the door to operate automatically in the event of a fire in the cabinet and permit the free and ready escape of gases, odors and fumes, thereby relieving the walls of the cabinet and the door from internal pressure, and whereby 55 in the event of a fire within the cabinet

danger of transmission of flames, fumes or gases to the building in which the cabinet is installed is prevented.

It is still further designed to provide a fire-proof cabinet having one or more compartments in which provision is made to support the record material and in which the support is connected to the door to limit outward swing thereof short of dead center so as to automatically close the door quickly 65 when the operator inserts or removes record materials from the holder and releases the door.

With the above and other objects in view the invention consists in the construction 70 and novel combination and arrangements of parts hereinafter fully described, illustrated in the accompanying drawings and pointed out in the claims hereto appended, it being understood that various changes in the 75 form, proportion and minor details of construction, within the scope of the claims, may be resorted to without departing from the spirit or sacrificing any of the advantages of the invention. 80

In the drawings:

Figure 1 is a vertical sectional view of two superimposed cabinets, partly in elevation, showing the record holder and the door closed in the upper compartment and 85 the position of the holder when the door is open.

Figure 2 is a detail perspective view of the record holder and its mounting.

Figure 3 is a transverse sectional view 90 through the holder.

Figure 4 is an enlarged fragmentary sectional view through the door jamb.

Referring now more particularly to the accompanying drawings wherein is illustrated one embodiment of my invention, in which both superimposed sections or units A and B are formed alike, it will be understood that the interiors of the compartments and the general make-up of the cabinet units 95 or sections or the cabinet itself, as the case may be, may be of any other suitable construction, the invention in the present case residing in a cabinet provided with a compartment for the filing and storage of record material and in which compartment there is located a holder for the record material which has a peculiar mounting and which has connection with the door of the compartment whereby to maintain the door 100 105 110 115 119

normally closed and locked, there being preferably disposed in the compartment wall, whatever the nature of the cabinet, an outlet to the atmosphere, whereby in the event of the generation of gases or fumes in the compartment they may be permitted to pass outwardly through the outlet and thereby relieve the walls of the cabinet and the door of strain incident to internal pressure, all as described in my co-pending application, filed May 31, 1916, Serial No. 237,550, and patented February 20, 1923, No. 1,445,975, and also in my co-pending application filed August 3, 1922, Serial No. 579,452.

In each unit or section A and B there is formed a compartment 4, provided with a door opening in which is formed a continuous rib 5 and a continuous groove 6. Each door 7 is preferably hinged at its lower side, as at 8, and it has its inner face formed with a continuous rib 9 and an adjacent continuous groove 10 adapted to cooperate with the continuous rib and groove form of door jamb for the purpose of forming a sealed closing of the door 7, there being flexible material 11 preferably disposed in each of the grooves for compression by the corresponding ribs to facilitate the prevention of leaking of moisture, fumes, gases or smoke from within, as well as from without.

A hanger 12 is disposed over the door opening of each compartment 4, and has a gravitating latch 13, designed to hold the door 7 normally locked. To open the door, upward movement of the gravitating latch 13 on its pivot 14 will permit outward swinging movement of the door. The door has a handle 15 to facilitate opening of the same, and if desired a cataloguing or index card holder 16 may be secured to the door.

Motion picture films are generally wound upon spools, such as shown in dotted lines at 17 in Fig. 1, and in the filing and storage of motion picture films, the main purpose for which the present invention is provided, I disclose a suitable holder 18, which in the construction shown is of a substantially segmental, truncated, cylindrical formation, constructed of suitable material, preferably metal, and composed of spaced sides 19 and 20, connected along their lower edges by the peripheral portion 21. The holder is open at the top to permit ready insertion and removal of the film spool 17.

The holder is mounted for a floating action, within the compartment toward and away from the door opening and to this end, the holder is supported above the bottom of the compartment on crossed oppositely inclined links 22 and 23. One link is longer than the other, as shown. The longer link extends upwardly from the front of the compartment and includes legs *a* and *b* and a bight or connecting portion *c* at the lower or front ends thereof. The inner or upper

ends of the legs *a* and *b* are provided with laterally inwardly directed pivot members 24, which are adapted to fit loosely in the horizontally aligning sockets 25 at the rear end of the holder. The shorter link 23 includes legs *d* and *e* connected at their rear lower ends by the connecting portion *f* and at their forward upper ends they are provided with pivot members 26 adapted to fit in the corresponding horizontally aligning sockets 27 of the holder.

In the bottom of the compartment, I fixedly secure a base plate 28 provided with spaced parallel upstanding hollow ribs 29. A rear pair of notches, forming oppositely disposed seats 30, is formed in the upstanding ribs 29 and adjacent the front end of the ribs they are each notched to provide a forward pair of seats 31. The seats 30 are designed to seat the connection portion *f* of the legs *d* and *e* of the shorter link 23. The forward horizontally aligning seats 31 of the ribs 29 are designed to seat the bight or connecting part *c* between the legs *a* and *b* of the link 22. When the links are thus connected to the holder and thus disposed in the front and rear pairs of seats, the holder is supported above the bottom of the compartment and above the upper face of the supporting plate 28 for a free and easy forward and rearward floating action.

To lock the links 22 and 23 in the aforesaid pairs of seats 30 and 31, I provide suitable locking pins 32, one for each hollow rib 29. The pins are long because of the length of the ribs and the distance between the pairs of seats 30 and 31 and are adapted to slide into and out of the hollow ribs and over the connecting portions *c* and *f*, of the respective legs of the respective links 23 and 22, so as to prevent accidental unseating of the links from said seats. The outer end of each locking pin 32 is provided with an inwardly and backwardly directed yieldable portion 33, terminating in a yieldable hook 34 for a snap connection with the bight portion *c* of the longer link 22, whereby to insure a firm and substantial locking of the locking pin 32 in the hollow ribs. These locking pins 32, including their portions 33 and 34, are resilient, yieldable or bendable, or otherwise formed so as to provide for yieldability, especially of the locking portions to permit a snapping connection thereof with the connecting portions between the legs *a* and *b* of the link 22 and to permit of ready disconnection of the hooks 34 from said connecting part *c*.

The holder is provided with an overhanging cam rib 35 on each side adjacent its upper open top and each cam surface extends substantially the entire length of the holder.

The holder is connected with the door by a link 36 including legs *g* and *h* and a con-

necting bight portion *i* between them at their forward ends. The inner ends of the legs are each provided with an eye 37 by means of which and a suitable fastening 38, 5 the legs *g* and *h* of the link 36 are fixedly secured to the sides of the holder under and adjacent the respective overhanging rib 35, whereby the holder in normal position lies upon the upper surface of the legs *g* and *h* 10 of the links 36 at the inner ends of the legs, as shown in the upper portion of Fig. 1, and also in Fig. 2. The connecting portion *i* of the legs *g* and *h* is detachably secured in a spring clip 39 whereby the link 36 may be 15 detachably secured to the door. The link 36 has a downward inclination in its connection with the holder and the door with the result that when the door 7 is swung outwardly on its hinge 8, the holder is 20 rocked on its supporting links 22 and 23, forwardly and upwardly to present the open upper part of the holder in such position with relation to the compartment door, opening so as to permit ready insertion of a record in the holder or an easy removal of the 25 record from the holder. As the holder swings forwardly and upwardly in the manner stated, and as may be seen clearly in the lower compartment of Fig. 1, the overhanging 30 ribs of the holder ride upon the greater portion of the legs *g* and *h* of the link 33, bending said legs and placing them under considerable tension and in any event under such tension that when the door is released 35 by the operator the tendency of the legs *g* and *h* to straighten out results in a spring-like action which accelerates the backward movement of the holder to its normal position and thereby facilitates closing of the 40 door by a quick, sharp, snap-like action, so that the door is open only while held by the operator in the act of taking out or inserting a record. The return swing of the door causes the upper edge of the door to engage 45 the latch 13 and swing it upwardly on its pivot 14 until the door has passed the inner end of the latch and taken proper tight, sealed joint connection with the door jamb when the latch falls downwardly and enga- 50 gages the outer face of the door at the joint between the upper edge of the door and the door jamb and thereby effects an automatic locking of the door.

As has been hereinbefore stated, and par- 55 ticularly illustrated, claimed and described in my co-pending application, filed Aug. 3, 1922 Serial No. 579,451, each compartment may be provided with an outlet to the atmosphere so that in the event of a fire 60 in the compartment incident to spontaneous combustion or from other causes, the gases or fumes may pass out through the outlet 39' to thereby preserve the walls of the compartment or to relieve them and the 65 door from internal strain and possible de-

struction incident to explosion of gases. The communication between the interior of each compartment and the passage 39' may be controlled by a suitable valve 40 pivoted at 41 in the passage 39 for a normal gravitational movement to its seat to thereby effectively close communication between the compartment and the respective outlet so as to prevent the entrance of gases or moisture into the compartment through the valve 75 outlet and whereby to permit the internal pressure due to the expansion of gases in the compartment to unseat the valve and pass on out through the outlet 39. Any gases passing out of the lower compartment in 80 Fig. 1 would pass up through the flue 41 past the outlet 39 and the valve 40, but as this feature of the invention forms part of the invention in my co-pending application, filed August 3, 1922 Serial No. 579,451, further description of the same herein is unnecessary.

What is claimed is:—

1. The combination with a cabinet having a compartment provided with a door hinged at its lower edge to the cabinet, of a holder mounted for rocking movement in the compartment and having overhanging, elongated ribs along its side edges, and a flexible connection between the holder and the door, whereby to rock the holder forwardly upon opening the door and whereby upon the forward rocking movement of the holder said ribs ride upon said flexible connection and flex the latter whereby to effect a quick closing of the door when the door is released.

2. The combination with a cabinet having a compartment provided with a door hinged at its lower edge to the cabinet, and a holder for the record material in the compartment, crossed links swingingly supporting the record holder in the compartment, the holder having overhanging cam ribs along its sides, and a U-shaped flexible link having detachable connection with the door and connected to the holder whereby to swing the holder forwardly when the door is opened and whereby said ribs flex said flexible link and effect a spring action of the sides of the link against said ribs when the door is released to effect a quick closing of the door.

3. The combination with a cabinet having a compartment provided with a door hinged at its lower edge to the cabinet, of a holder for record material disposed in the compartment, a base member secured in the bottom of the compartment and provided with spaced parallel hollow ribs provided with an inner and an outer pair of notches forming seats, a link member seated in the rear pair of seats and having pivotal connection with the forward end of the holder, a second link member seated in the

- forward pair of seats and having pivotal connection with the rear end of the holder whereby to normally maintain the holder within the cabinet, a link connection between the holder and the door whereby to swing the holder forwardly when the door is opened, and means between the holder and the last mentioned link connection to actuate the latter to effect a quick return movement of the door to closed position when released.
4. The combination with a cabinet having a compartment provided with a door hinged at its lower edge to the cabinet, of a holder for the record material disposed in the compartment, a base member mounted in the bottom of the compartment and provided with longitudinally disposed parallel hollow ribs, the ribs being notched to provide a rear pair of aligning seats and a forward pair of aligning seats, a substantially U-shaped link having its inner portion mounted in the rear seats of said ribs and pivotally connected to the forward end of the holder, a second substantially U-shaped link seated in the forward pair of seats of said ribs and having pivotal connection with the rear end of said holder, the second U-shaped link being longer than the first mentioned U-shaped link, whereby to maintain the holder normally within the cabinet and a substantially U-shaped link having detachable connection with the door and also having pivotal connection with the holder whereby upon opening the door of the compartment the holder is swung forwardly to permit access to the holder, the said links between the base member and the holder supporting the holder above the base member and coacting with the connection between the holder and the door to prevent the door from swinging beyond dead center and thereby effecting a closing pull upon the door by the holder when the door is released.
5. The combination with a cabinet having a compartment provided with a door hinged at its lower edge to the cabinet, of a holder for the record material disposed in the compartment, a base member mounted in the bottom of the compartment and provided with longitudinally disposed parallel hollow ribs, the ribs being notched to provide an inner pair of aligning seats and a forward pair of aligning seats, a substantially U-shaped link having its inner portion mounted in the rear seats of said ribs and pivotally connected to the forward end of the holder, a second substantially U-shaped link seated in the forward pair of seats of said ribs and having pivotal connection with the rear end of said holder, the second U-shaped link being longer than the first mentioned U-shaped link, whereby to maintain the holder normally within the cabinet and a substantially U-shaped link having detachable connection with the door and also having pivotal connection with the holder whereby upon opening the door of the compartment the holder is swung forwardly to permit access to the holder and whereby upon release of the door the holder moves back into the cabinet and closes the door.
6. The combination with a cabinet having a compartment provided with a hinged door, of a holder movably mounted in the compartment, a flexible connection between the holder and the door, the holder and connection between the holder and the door serving to normally maintain the door closed, and means engageable with the flexible connection between the holder and the door to gradually place the said connection under tension as the door is opened so that when the door is released the latter is given a sharp return movement to closed position.
7. The combination with a cabinet having a compartment provided with a door hinged at its lower edge to the cabinet, of a holder for the record material disposed in the compartment, a base member mounted in the bottom of the compartment and provided with longitudinally disposed parallel hollow ribs, the ribs being notched to provide an inner pair of aligning seats and a forward pair of aligning seats, a substantially U-shaped link having its inner portion mounted in the rear seats of said ribs and pivotally connected to the forward end of the holder, the second substantially U-shaped link seated in the forward pair of seats of said ribs and having pivotal connection with the rear end of said holder, the second U-shaped link being longer than the first mentioned U-shaped link, and a substantially U-shaped link having detachable connection with the door and also having connection with the holder whereby upon opening the door of the compartment, the holder is swung forwardly to permit access to the holder, the said links between the base member and the holder supporting the holder above the base member and coacting with the connection between the holder and the door to prevent the door from swinging beyond dead center, the holder having cam ribs on opposite sides adapted to ride upon the connection between the holder and the door when the door is open so as to flex said connection to give it a spring action when the door is released so as to effect quick return of the holder to normal closed position.
8. The combination with a cabinet having a compartment provided with a door opening and also with an outlet leading to the atmosphere, a holder rockingly mounted in the compartment above the bottom of the compartment, a door hingedly connected to the cabinet, a spring clip secured to the inner face of the door, the holder having cam ribs on its sides, a link detachably secured

in said spring clip of the door and embracing the holder and upon which the cam ribs of the holder ride when the door is opened, so as to flex said connection to give a spring 5 action to the connection when the door is released as to accelerate the closing of the door.

9. The combination with a cabinet provided with a door opening, a swinging door 10 for said opening, a record holder swingingly mounted in the cabinet, a flexible connection between the door and holder whereby upon opening the door the holder is swung forwardly, the holder having means to flex said 15 connection between the holder and door so as to place the connection under tension when the door is open to thereby provide a sharp return of the door to closed position when released by the operator.

10. A record holder for filing and storage cabinets, comprising a base provided with upstanding longitudinal hollow ribs, the ribs having notches therein to form front and rear pairs of seats, links swingingly mounted 20 in said seats, a container pivotally connected to the links and supported thereby above the base for swinging movement, and locking devices removably fitted in said ribs and crossing the seated portions of the links to 25 lock the links in their seats.

11. A record holder for filing and storage cabinets, comprising a base provided with spaced hollow ribs, the ribs having notches therein to form a front pair and rear pair 35 of seats above the base, a link mounted in the front pair of seats, a link mounted in the rear pair of seats, the first mentioned link being longer than the second mentioned link, and a container having connection with 40 the links and supported thereby above the base.

12. A record holder comprising a base provided with upstanding hollow ribs having notches to form a front pair of seats 45 and a rear pair of seats, and supporting connections between the holder and said seats, locking devices connected with the ribs and 50 slidable over portions of said connections between the holder and seats, the outer ends 55 of the locking devices being yieldably connected with a portion of one of the aforesaid connections between the holder and the base.

13. In a filing and storage cabinet, having a compartment therein, the compartment having a door opening, a door for the opening, a base plate disposed on the bottom of the compartment and having longitudinally disposed upstanding members, a record holder in the compartment, link connections between the record holder and the upstanding members of the base plate to swingingly support the record holder, the record holder having cam ribs on opposite sides thereof, and a U-shaped link detach-

ably connected to the inner side of the door 65 and secured to the sides of the holder under said cam ribs at the rear end of the latter, whereby upon opening the door the cam ribs ride upon the flexible U-shaped link and flex the same to place the link under tension while the door is open so that upon release of the door by the operator the tensioned U-shaped link will spring back to normal condition and effect a quick return of the holder to normal position and of the 70 door to closed position simultaneously with the movement of the holder to normal position.

14. A record holder for filing and storage cabinets, comprising a sheet metal base provided with upstanding hollow ribs having notches to form a front pair of seats and a rear pair of seats located above the base, a holder, connections between the holder and said seats, locking devices connected with 80 the ribs and slideable over portions of the connections between the holder and seats to lock said connections in said seats.

15. A holder for filing and storing records in a cabinet, comprising a base provided 90 with spaced, parallel, upstanding ribs, the ribs having seats therein located above the base, a holder disposed over the base, supporting connections between the holder and the seats, and means for locking the supporting connections in said seats.

16. A holder for filing and storing records in a cabinet, comprising a base provided with spaced longitudinal hollow ribs, the ribs having notches therein to provide 100 front and rear pairs of seats, a holder disposed over the base, a U-shaped link having its bight portion mounted in the front pair of seats and having its legs pivotally connected to opposite sides of the rear end of the holder, a U-shaped link having its bight portion mounted in the rear pair of seats and pivotally connected to opposite sides of the holder at the front end of the latter, and pins 110 slideable into the hollow ribs past the seats over the bight portions of said links to lock the links in said seats.

17. A holder for filing and storing records in a cabinet, comprising a base provided with spaced longitudinal hollow ribs, the ribs having notches therein to provide front and rear pairs of seats, a holder disposed over the base, a U-shaped link having its bight portion mounted in the front pair of seats and having its legs pivotally connected to opposite sides of the rear end of the holder, a U-shaped link having its bight portion mounted in the rear pair of seats and pivotally connected to opposite sides of the holder at the front end of the latter, and pins slideable into the hollow ribs past the seats over the bight portions of said links 120 and having their outer ends detachably se-

cured to the bight portions of the first mentioned link whereby to lock said links in said seats.

18. The combination of a compartment having a door opening, a hinged door for the opening, a base plate mounted upon the bottom of the compartment and provided with upstanding ribs, crossed, U-shaped links swingingly seated on said ribs, a holder pivoted to said links and supported thereby within the links above the base plate, and a connection between the holder and the door whereby upon opening the door the U-shaped links are swung forwardly and the holder swung upwardly and forwardly to permit insertion or removal of records from the holder through the door opening, said links limiting outward movement of the door and holder short of dead center whereupon release of the door the door closes automatically under the influence of the holder, the said connection between the door and holder being flexible and the holder having means to engage the said connection to flex it when the door is opened so as to accelerate the closing movement of the door.

19. A holder for filing and storing records comprising a base provided with a pair of longitudinally disposed hollow ribs having seats in their upper edges, a holder disposed over the base, and crossed supporting connections between the holder and the seats.

20. In a filing and storage cabinet including a compartment provided with a door opening, a door for the opening, a sheet metal base plate disposed in the compartment and having upstanding members hollow throughout their length, a record holder in the compartment, connections between the upstanding members and the holder to swingingly support the holder in the compartment, devices extending longitudinally into the hollow members to lock the said connection to said members, and connecting means between the holder and the door whereby to swing the holder upon opening and closing movements of the door.

21. In a filing and storage cabinet including a compartment provided with a door opening, a door for the opening, a base plate disposed in the compartment and having hollow upstanding members provided with seats, a record holder in the compartment, elements seated in the seats of the upstanding members and having connection with the holder to swingingly support the holder in the compartment, connecting means between the holder and the door whereby to swing the holder upon opening and closing movements of the door, and

means operable within the hollow members for locking the holder supporting connections in the seats of said upstanding members.

22. A holder of the character described comprising a base provided with upstanding ribs hollow throughout their length, the ribs having seats formed in their upper edges, a holder disposed over the base, supporting connections between the holder and seats and having their lower portions engaged in said seats, and locking elements sliding into and out of the hollow ribs for passage over said seats to lock said connections in the seats and having yieldable portions engaging one of the supporting connections to prevent accidental dislodgment of the locking devices.

23. A record holder comprising a base provided with a pair of longitudinally disposed upstanding hollow ribs having notches to form a front pair of seats and a rear pair of seats, supporting elements bridging said seats and connected to the holder, and locking devices connected with the ribs and slideable over said bridging portions of said connecting elements between the holder and seats, the outer ends of the locking devices being yieldably and detachably connected with the bridging portion of one of the aforesaid connections between the holder and the base.

24. The combination with a cabinet provided with a hinged door, of a holder movably mounted in the cabinet, a flexible connection between the holder and the door, the holder and connection between the holder and the door serving to normally maintain the door closed, and means whereby to place the flexible connection under tension as the door is opened so that when the door is released the latter is given a sharp return movement to closed position.

25. The combination of a cabinet provided with a door opening and also having an outlet leading to the atmosphere, a record holder swingingly mounted in the cabinet, a door hingedly connected to the cabinet, a clip secured to the inner face of the door, a link detachably secured to the clip and having connection with the holder, and means on the holder for engagement with the connection between the holder and door to flex said connection when the door is opened so as to give a spring action to the connection when the door is released to accelerate the closing movement of the door.

In testimony whereof I have hereunto set my hand.

EDWARD W. SALMON, Jr.
